(57) **CLAIM**

The ornamental design for a pallet container with a door, as shown and described.

DESCRIPTION

FIG. 1 is a perspective view taken from an upper right side of the pallet container with a door, according to the invention; and,

FIG. 2 is a perspective view taken from a lower right side of the pallet container with a door shown in FIG. 1.

The surfaces or portions of the article not shown in the drawing or described in the specification form no part of the claimed design.
